SURFACE ORNAMENTATION OF WALLS, &c.

No. 16,407.

Patented Dec. 8, 1885.

UNITED STATES PATENT OFFICE.

FREDERICK MANKEY, OF WILLIAMSPORT, PENNSYLVANIA.

DESIGN FOR SURFACE ORNAMENTATION OF WALLS, &c.

SPECIFICATION forming part of Design No. 16,407, dated December 8, 1885.

Application filed July 18, 1885. Serial No. 171,993. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., of which the following is a specification, reference being had to the accompanying photograph, forming part hereof.

My design consists in a figure of the shape of a Maltese cross formed upon the surface by four trilateral pyramidal elevations, A, B, C, and D, separated by diagonal channels E and F. This figure is repeated in regular rows longitudinally and transversely the panel, the rows being separated by transverse channels G and longitudinal channels H.

I claim—

The design for ornamental panels or moldings, substantially as herein shown and described, consisting of a Maltese cross formed by four trilateral pyramids, A B C D, raised upon the surface of the panel, and separated by diagonal channels E and F, the said figure being repeated in rows lengthwise and transversely the panel, and the said rows being separated by transverse channels G and longitudinal channels H, a different grain-marking appearing upon said elevations from that which appears in said channels.

FREDERICK MANKEY.
